(57) **CLAIM**

The ornamental design for a confectionery product container having a cap as shown.

DESCRIPTION

FIG. 1 is a top perspective view of a confectionery product container having a cap showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines shown in the drawings form no part of the claimed design.

1 Claim, 6 Drawing Sheets
